MODULATING COMPRESSOR CAPACITY CONTROL

Karl M. Gerteis, Syracuse, N. Y., assignor to Carrier Corporation, Syracuse, N. Y., a corporation of Delaware

Application August 30, 1944, Serial No. 551,957

7 Claims. (Cl. 230—24)

1

This invention relates to reciprocating compressors and more particularly to methods of and means for varying the effective displacement of a compressor responsive to variations in load requirements.

The general object of the invention is to provide for variably controlling the opening of one or more suction valves under control of a regulating device reflecting changes in load conditions.

In employing compressors, more particularly, refrigerant compressors, it is highly desirable to regulate capacity in order to obtain required refrigeration effect with minimum loss of efficiency. Various attempts have been made to achieve modulating control of capacity, as by retaining open suction valves, and by other means which maintain valves in fully opened or closed positions.

Applicant provides a more effective solution by modulating the capacity of a compressor by regulating the graduated closing of one or more valves to reflect variations in load conditions. As a result, the disadvantages of step control are eliminated and infinite variation in capacity throughout the effective range of the compressor may be achieved. Thus as the compressor operates under decreasing or increasing partial load conditions, the valve action varies directly to compensate for such changes in condition.

A feature of the invention resides in the use of oil pressure varied responsive to changes in load conditions to govern the adjustable positioning of a suction valve.

Another feature of the invention resides in the provision of a pair of springs, one at each side of a suction valve, the extent of compression of one of them being dependent upon variations in oil pressure reflecting changes in load conditions.

Another feature of the invention covers the use of an oil actuated piston operating a lever device for varying the compression of a spring bearing against one side of a suction valve to determine its time of closing as the load varies.

Another feature covers utilizing the pressure applied by an oil actuated piston in combination with the pressure exerted by a piston of the refrigerant compressor for governing the time of closing of a suction valve.

Another feature covers the regulation of oil pressure for actuating the positioning of the suction valve responsive to temperature or pressure conditions of an area served by the system of which the compressor is a part.

Another feature of the invention assures the

2

positioning of applicant's control so that the compressor with respect to those cylinders to which the control is applied, starts completely unloaded.

5 These and other features will be more apparent from the following description of a typical form of the invention, applied to a refrigerant compressor, to be read in connection with the accompanying drawings in which

10 Fig. 1 is a diagrammatic view of a refrigerating machine having a plurality of cylinders, applicant's modulating control being shown applied to one of the cylinders, although, in practice, it may be applied to several of them.

15 Fig. 2 is a diagrammatic view, showing the regulating means for variously controlling the time and duration of opening of a suction valve on one cylinder of a compressor.

Fig. 3 shows a detail view of a valve, actuated 20 by suction pressure, employed for regulating the unloading action; and

Fig. 4 shows a control arrangement for regulating oil pressure for modulating a compressor capacity control responsive to variations in temperature conditions of an area served by an air conditioning system of which a compressor is a part.

Considering the drawings, similar designations referring to similar parts, numeral 5 generally 30 designates a compressor having a plurality of cylinders 6, 7, 8 and 9. The compressor may be of conventional design and includes a crank case 10, the bottom of which serves as an oil sump 11; and the operating mechanism includes 35 the usual crank shaft 12, pistons 13, connecting rods 22 and other structural elements normally employed for compressing gases, all of which form no essential part of the invention, but which it will be understood are present to form an operable compressor.

In various applications to which a compressor 40 may be applied, more especially a refrigerant compressor, the need for varying the output responsive to different or changing load requirements is often great. Applicant provides a modulating control adapted to be applied to one or

45 more cylinders of a compressor for governing the action of the suction valve serving the cylinder to which the control is applied. Unlike previous expedients for controlling compressor capacity, the action of applicant's valve is so regulated that the time and extent of opening of said valve is correlated with variations in load requirements with the result that compressor out-

put will automatically be increased or decreased exactly to compensate for changes in load.

First considering the general diagrammatic arrangement of Fig. 1, pump 14 supplies oil from sump 11 to feed line 15. The oil passes through orifice 16 and then applies pressure within supply line 17 depending upon the amount of oil flowing through regulating line 18 which is routed to control valve 19 from which the oil fed thereto is returned to the sump through return line 20. Suction pressure connecting line 21 subjects control valve 19 to the suction pressure in manifold 52.

Now considering the detailed view shown in Fig. 2 of applicant's modulating control as applied to any desired cylinder, a power element 23 has a piston 24 therein with a piston rod 25 connected to a forked operating lever 26 at pivot 27. The lever is connected at pivot 28 to power element cover 29. A spring 30 is positioned about piston rod 25 between the inverted piston head 24 and cover 29. Actuating shoes 31 at the ends of the forked operating lever 26 bear against spring supporting ring 32 to cause the ring to move up and down upon the outer wall of the cylinder guided by body portion 33 of ring 32 which is positioned concentrically about the cylinder.

A plurality of capacity control springs 34 are mounted upon supporting ring 32 within suction ports 35 of cylinder sleeve 36.

Suction valve 37 is positioned between capacity control springs 34 and suction valve springs 38, the valve springs being recessed in the usual manner within valve plate 39.

The control valve 19 which regulates the pressure applied to power element 23 is shown in detail in Fig. 3. The oil from pump 14 feeds into valve 19 through regulating line 18 entering port 40. The oil passes through drilled passageway 41 past valve seat 42 into passageway 43 depending upon the position of valve needle 44, the position of which is determined by the action of bellows element 45.

The bellows element includes cup 46 having therewithin a range adjustment spring 47 whose compression is adjusted by the regulating screw 48. The cup actuates a series of push pins 49 which, in turn, bear against collar 50 for positioning the valve needle. The collar has exerted thereagainst the pressure of spring 51 in opposition to the force supplied thereto by the pins.

Suction pressure reflecting the condition in suction manifold 52 is applied through line 21 and passage 53 to the inside of bellows 45. The result is that as the suction pressure drops, the cup 46 will move downwardly to cause pins 49 to open the valve, causing an increase in oil to flow through regulating line 18 with the result that oil pressure through line 17 exerted upon power element 23 will drop. On the other hand on an increase in load, when the suction pressure rises, the pressure in the bellows will correspondingly rise to overcome the pressure of spring 47, with the result that spring 51 will serve to tend to push the valve needle to closed position. The pins 49, in this event, will not be able to overcome the pressure of spring 51 since the cup will be sufficiently lifted due to the increased pressure within the bellows to keep the pins from pushing downwardly collar 50 in which the valve needle is held.

The push pins 49 fit within holes in the valve casting so that they ride up and down resting against the bottom of the cup 46 and the top

of collar 50. As the cup tends to rise upon expansion of the bellows, the action of spring 51 will serve to close the valve and make the pins ride up, whereas when the bellows contracts, the pressure of spring 47 which is then greater than the pressure of spring 51, will cause the pins to push down the collar 50 and hence open the valve.

In practice, with the system shown in Figs. 1 and 2, including a control valve 19 as shown in Fig. 3, it will be noted that when the compressor is started up, substantially no oil pressure will exist at the moment of starting. Consequently, there will be no oil pressure in line 17 and the piston 24 of power element 23 will be down. Thus, actuating shoes 31 will be in uppermost position holding spring supporting ring 32 in top position with suction valve 37 completely open. The compressor will, therefore, start in an unloaded condition, as is most desirable.

Under practical operating conditions, when the suction pressure is above the point for which regulating screw 48 on valve 19 is set, then the modulating mechanism will be inoperative. However, upon a drop in suction pressure below said set point, the valve needle will open to reduce the oil pressure in an amount depending upon the reduction in load, as reflected by the drop in suction pressure. The effect is to apply a varying pressure upon the power element 23 corresponding to the variation in partial load. Consequently, the suction valve 37 will be opened at a point in the stroke and then closed responsive to building up of pressure upon the compression stroke to provide less than full compressor capacity corresponding to the drop in load.

In Fig. 4, a modified form of control is illustrated in combination with an air conditioning system served by a compressor equipped with applicant's invention. In this case, a multi-cylinder compressor has one or more of the cylinders equipped with the capacity control already shown in Fig. 2. The gas discharged from the compressor goes to a condenser 54, receiver 55, then through expansion valve 56 to an evaporator 57 employed for cooling the air of enclosure 58; the gas returning to the compressor through line 59 to close the usual cycle.

Instead of operating applicant's modulating control responsive to variations in suction pressure, a regulating device 60 is provided operative responsive to a thermostatic bulb 61 within the conditioned enclosure 58.

The position of diaphragm 62 of regulating device 60 depends upon the pressure within lower diaphragm chamber 63 and the spring pressure of spring 64.

Upon a decrease in room temperature, indicating a drop in load, diaphragm 62 will tend to move down to open the valve 65 in an amount corresponding to the reduction in load. On the other hand, upon an increase in temperature within the conditioned enclosure the pressure within chamber 63 will increase to the point where it overcomes the pressure of spring 64 and correspondingly tends to close the valve 65. The oil pressure in line 17 will then rise to cause the piston in the power element to go up whereupon the supporting ring 32 will drop and suction valve 37 close to resume full load operation. Of course, where partial load conditions still obtain, the action will be the same as with the control of Fig. 3 in that the time and extent of opening of the suction valve will be

governed by the partial load condition which regulates the spring action on the valve as opposed to the compression on the upward stroke of the cylinder.

Thus, applicant provides a sensitive modulating control with unlimited range for every load condition which arises over practical operating conditions. The compressor starts in unloaded condition. Immediately thereafter, however, it may operate at full load conditions; and thereafter whenever partial loads are encountered the capacity will be increased and decreased to compensate for such variations in partial load to give exactly the capacity needed to maintain any given condition.

It will be obvious to those skilled in the art that various changes may be made without departing from the spirit of the invention and therefore the invention is not limited to what is shown in the drawings and described in the specification but only as indicated in the appended claims.

I claim:

1. A system of modulating capacity control for reciprocating compressors comprising means for pumping oil, an oil actuated power element, a line including an orifice therein for delivering oil under pressure to said power element, a modulating means operative responsive to variations in load conditions affecting a compressor for modulating the oil pressure in said line, a suction valve, and means operated by the power element for varying pressure applied against the valve to determine its time of closing.

2. A modulating capacity control for a reciprocating compressor, including a suction valve, a suction valve spring bearing on one side of the valve, a capacity control spring bearing against the valve on the other side thereof and means responsive to varying oil pressure for compressing the capacity control spring depending upon variations in load conditions affecting the compressor.

3. A modulating capacity control for reciprocating compressors including a power element, a piston within the power element, means for applying oil pressure to said power element opposed by spring pressure thereon, an operating lever under control of the power element, a suction valve, means for applying pressure against the suction valve, said means being actuated by said lever and means for varying the oil pressure exerted on said power element for corre-

spondingly varying the pressure applied against said suction valve.

4. In combination with a compressor, including a modulating capacity control therefor, a suction valve, a pair of springs positioned on opposite sides of the valves, means for compressing one of the springs in accordance with variations in load affecting the compressor.

5. In combination with a reciprocating compressor, a modulating capacity control for regulating the time of closing of a valve, said combination including a valve, means for applying a force in one direction against one side of said valve, means for applying a force in the opposite direction against the opposite side of said valve, means for varying the force applied against the opposite side of the valve responsive to variations in load affecting the compressor.

6. In a combination of the character described, 20 a compressor having a plurality of cylinders, a modulating capacity control applied to certain of said cylinders, said capacity control including an operating lever on each of a plurality of said cylinders, an oil pressure actuated power element controlling the movement of said lever, a spring supporting ring adapted to be variously positioned by said lever, a capacity control spring supported by said ring and bearing against one side of said valve, means for supplying spring 25 pressure against the other side of said valve, an oil pump for lubricating the compressor, and means for supplying oil from said pump to the power element at a pressure depending upon the load affecting the compressor to govern the pressure exerted by said first mentioned spring bearing 30 against the valve.

7. A system for varying the output of a compressor including a valve in the compressor, means for exerting spring pressure on opposite 35 sides of the valve, a power element operated by oil pressure for modulating the spring pressure applied to one side of the valve, an area to be conditioned served by the compressor, and means operative responsive to variations in atmospheric conditions within said area for varying the oil pressure applied to said power element in such a manner that said spring pressure controlled thereby is varied to adjust the 45 time of closing of the valve to regulate capacity output of the compressor in accordance with changing load conditions in said area.

KARL M. GERTEIS.
